UNITED STATES PATENT OFFICE.

JAMES P. QUALEY AND AUGUST F. WUILLEMIER, OF CLEVELAND, OHIO.

FEED-WATER REGULATOR.

Application filed March 5, 1925. Serial No. 13,221.

This invention is concerned with feed water regulators and the general object of our invention is the provision of an automatic feed water regulator which will operate in an efficient manner to maintain the water level in a boiler of a heating system substantially normal but which in case of an emergency due to a flooded condition of the boiler, will also operate to connect the boiler 10 to a drain line.

More specifically our invention is directed to the provision of a liquid container operated device which will control the feed water line and an overflow drain line of a boiler.

Another object of our invention is the provision of a simple apparatus for the foregoing purposes which may be economically manufactured and installed and which will operate under the varying thermal conditions of a heating system to maintain a normal water level in the boiler of the system.

Other objects of our invention will hereinafter be set forth in the following description which refers to the accompanying drawings illustrating a preferred form thereof. The essential characteristics are summarized in the claims.

In the drawings Fig. 1 is a side elevation with parts in section of a boiler equipped with our novel feed water regulating means; Fig. 2 is a front elevation of our device; Fig. 3 is an enlarged cross-sectional view taken substantially along the line 3—3 of Fig. 2 and showing a valve structure for controlling the feed water line and an overflow drain line of the boiler; Fig. 4 is an enlarged cross-sectional view taken substantially along the line 4—4 of Fig. 3 and Fig. 5 is an enlarged cross-sectional detail taken 40 through the valve mechanism substantially along the line 5—5 of Fig. 3.

Devices of the general character with which our invention is concerned, usually embody some kind of a flexible connection in the form of a rubber hose or flexible metallic conduit, the flexing of which interferes with a sensitive operation of the liquid container. Likewise these various devices make no provision for an overflow drainage of the boiler being serviced by the feed water line. Our experience has demonstrated that none of these devices should be relied upon to automatically control the feed water to a boiler, and particularly a boiler in a heating system, for it frequently occurs that a considerable amount of water

in the form of condensate may be temporarily retained by the heating system to which the boiler is connected and that this condensate may return to the boiler only 60 after such a device has functioned to over-feed water to the boiler with a consequent flooding of the boiler.

Our invention contemplates the provision of an overflow drain which may be automatically controlled simultaneously with the automatic control of the feed water line to the boiler and a preferred form of our device incorporates the use of only a single valve preferably of the Corliss type which 70 valve may be connected in the feed water line and the overflow drain line of the boiler and be operated by a closed liquid container which is in communication with the boiler under all conditions whereby the varying 75 water level in the container will cause a swinging movement thereof in opposition to a counterpoise mechanism.

As shown in Figs. 1 and 2 of the drawings a preferred form of our invention may comprise a feed water line 10 connected to an outside source of water supply and which is connected by a lower stretch of pipe 10^a to the lower part of the boiler 12 and an overflow drain line extending to a sewer, both pipe lines being connected to the body 14 of a control valve. The valve 14 may be of the tapered sleeve or Corliss type operated by a liquid container 16 and a counterpoise or weight 17 and accordingly the container 16 is mounted on a pipe extension 18 projected at right angles to a hollow valve stem 19 rigidly secured to the valve port member 20. On the opposite side of the stem 19, a weight arm 22 may be rigidly attached for suspending the counterpoise or weight 17 in balanced relation to the weight of the tank 16 plus the weight of its normal liquid content.

As shown in cross-section in Fig. 3 the valve stem 19 may comprise a pipe in threaded engagement with the tapered port member 20, and a T fitting 19^a may comprise the connecting means between the container arm 18 and the stem 19. The valve port member 20 may have the ports thereof, as shown in Fig. 5, arranged in such manner that regardless of the operative position of the tank 16, the interior of the container will, under all conditions, be in communication with the interior of the boiler 12 wherefore the liquid level in the container 16 will

always correspond to the liquid level in the boiler 12.

The port 24 is normally out of alignment

- 5 with the feed water passage 25 of the valve body branch 26 which comprises the connection for the high pressure or city pressure side 10 of the feed water line 10—10^a. The large port 27 is of such angular displacement, relative to the port 24, that the 10 interior passage 28 of the tapered valve member 20 will under all operating conditions be in communication with the passageway 29 formed in the valve body branch 30 which affords connection for the stretch 10^a 15 of the feed water line 10—10^a.

It will thus be seen that through the part 10^a of the feed water line, the interior of the container is in communication with the interior of the boiler through the line 10^a,

- 20 passageway 29, valve passageway 28, stem 19 and pipe arm 18. It will also be seen that the port 24 will be out of alignment with the feed water line 10 when the tank is in a normal position as shown in Fig. 2, which 25 position corresponds to the normal water level in the boiler. The angular span of the port 27 is such that if the container is depressed or swings to a position lower than the normal position shown in Fig. 2, the port 30 27 will be brought into communication with a passageway 34 formed in the branch 35 of the valve body 14 and this branch constitutes a connection for the boiler overflow drain 36.

- 35 The valve has three major operating positions; namely the water feeding position when the container 16 is elevated due to the presence of a low water level therein; a normal position in which the drain line and feed water line are closed and which position corresponds to the normal water level in the boiler and container; and finally an overflow position when the feed water line is closed and the drain line open, which position corresponds to a depressed or lowered 40 position of the container due to the presence of a high water level therein.

- 45 In order to prevent the formation of an air bell in the top region of the container 16, when the water level therein is varying, it is necessary that the top of the container be 50 vented in a practical way without endangering the escape of steam. This vent may comprise a conduit between the top region of the container and the top region of the boiler and a preferred form of such connection is illustrated in the drawings as comprising a pipe line 40 extending from the top of the container downwardly to a fitting 41 which comprises a part of the valve stem 19. The fitting is closed at one end as shown at 55 42 and may be in the nature of a T affording connection for an extension 19^b of the valve stem which is not in communication with the part 19. The extension 19^b may be supported 60 by a bracket arm 42 which may be se-

cured to the feed water line 10^a in any suitable manner, preferably by a clamping plate 43.

The journal end 44 of the bracket 42, which supports the extension 19^b of the valve stem, may be in the form of a stuffing box comprising a gland 46 which permits an oscillating movement of the extension 19^b but which assures a close fitting connection between the container, vent line 40 and a pipe 75 line 50 which is connected to the top region of the boiler as shown in Fig. 1.

The device hereinbefore described is operable the greater part of the time from the normal position shown in Fig. 2 to an upward position to feed water to the boiler and swings downwardly only under an emergency condition when an unusual return flow of condensate from the heating system to the boiler suddenly takes place and we prefer to provide a simple auxiliary counterpoise mechanism which will function to maintain the container 16 in a normal position but which will permit a downward movement of the container when such unusual return of condensate takes place.

As shown in Figs. 2 and 4, this auxiliary counterpoise mechanism may comprise an arm 52 having a fulcrum bearing 53 resting on the horizontal stretch 42^a of the bracket 42. The arm 52 has a forward extension 54 which serves as a rest for the pipe arm 18 supporting the container. The opposite end of the arm 52 is provided with a counterpoise or weight 56 which tends to oppose the downward movement of the container 16. An upward swinging of the extension 54 is prevented by a short bracket 60 formed on or secured to the bracket 42 which extends over the top of the arm 52 but which will permit a downward swinging thereof. It will thus be seen that if a slight elevation of the water above the normal water level in the boiler should take place the overflow drain line will not be opened if this slight increase in weight in the container 16 is supported by the weight 56. If, however, an unusual elevation of the water level in the boiler takes place thus greatly increasing the normal weight of the container 16, the opposing influence of the auxiliary weight 56 will be overcome and the container will depress the arm 52 thus swinging the valve 20, to open the boiler to the overflow drain line 36, through pipe line 10^a, passageway 29 valve port 27 to valve passage 34 to the drain.

From the foregoing description of our invention, it will be obvious that we incorporate in an automatic feed water regulator, a Corliss valve structure which is not subjected to wire drawing or wear due to leakage from the high pressure side of the feed water line and that what wear which may take place may be automatically taken

up by reason of the tapered surface of the movable part of the valve. If desired, a spring may be provided as shown at 61 in Fig. 3 to automatically take up such wear 5 to maintain a uniform tension on the movable valve parts. The vent connection by reason of the fact that the movable and stationary parts thereof are joined to have an axis coincident with the axis of the valve 10 gives a uniform friction which may be originally provided for by adjustment of the weight 17 on the counterpoise arm 22 and that the frictional opposition to the movement of the valve stem 19 will be constant 15 under varying operating conditions, thus greatly increasing the efficiency of the mechanism as well as assuring an accurate and ready response thereof to the varying water level conditions in the boiler. Furthermore 20 it will be obvious that all of the foregoing desirable characteristics in an automatic feed water regulator may be obtained in our invention in a very simple manner involving the use of but a few elements 25 which may be readily and economically manufactured.

We claim:

1. In a heating system the combination of a boiler, a feed water line connected to the boiler, a valve controlling said line, a closed movable container connected to the upper region of the boiler and through said valve to the feed water line and a boiler overflow drain line connected to the valve. 30
2. In a heating system the combination of a boiler, a feed water line for the boiler, a closed movable container connected to the upper region of the boiler and to the feed water line, a boiler overflow drain line and a common means operated by movement of the container for controlling the feed water line consequent to water level variations in the boiler and for connecting the boiler to said overflow drain line. 40
3. In combination, a boiler, a feed water line, a boiler overflow drain line, a single valve controlling the feed water line and drain line and a liquid container connected to the boiler and valve for operating the valve and mounted to be movable. 45
4. In combination a boiler, a feed water line, a boiler overflow drain line, a valve controlling the drain line and feed water line, a container connected to the boiler through the valve and adapted to operate the valve, a counterpoise mechanism for the container for operating the valve to open the feed water line and a second counterpoise mechanism for maintaining the container at a definite position when the water level in the boiler is substantially normal. 55
5. In a heating system the combination of a boiler, a feed water line connected to the boiler, a valve controlling said line, a closed container connected to the upper region of 60

the boiler and through said valve to the feed water line and a boiler overflow drain line controlled by a movement of the container.

6. In a heating system the combination of a boiler, a feed water line for the boiler, a closed container connected to the upper region of the boiler and to the feed water line, a boiler overflow drain line and a sleeve valve operated by the container for controlling the feed water line consequent to water level variations in the boiler and for connecting the boiler to said overflow drain line. 70

7. In combination, a boiler, a feed water line, a boiler overflow drain line, a single valve controlling the feed water line and drain line, a container connected to the boiler and valve for operating the valve and a vent connection between the boiler and container having a pivotal connecting means coincident with the valve axes. 80

8. In combination a boiler, a feed water line, a valve controlling the feed water line, a container connected to the boiler through the valve and adapted to operate the valve, a counterpoise mechanism for the container for operating the valve to open the feed water line and a second counterpoise mechanism for maintaining the container at a definite position when the water level in the boiler is substantially normal. 90

9. In a heating system the combination of a boiler, a feed water line for the boiler, a closed container connected to the upper region of the boiler and to the feed water line, a boiler overflow drain line, a common means operated by the container for controlling the feed water line consequent to water level variations in the boiler and for connecting the boiler to said overflow drain line including a counterpoise mechanism for the container and an auxiliary counterpoise mechanism active to restore the container to a normal position after an overflow draining of the boiler has been effected. 100

10. In combination a boiler, a feed water line, a boiler overflow drain line, a single valve controlling the feed water line and drain line, a container connected to the boiler and valve for operating the valve, and a double counterpoise mechanism active in two stages to maintain the container in a normal position. 110

11. In a heating system the combination of a boiler, a feed water line connected to the boiler, a valve controlling said line, a closed container connected to the upper region of the boiler and through said valve to the feed water line, a hollow valve stem and a bracket secured to the feed water line and pivotally supporting the stem and container. 120

12. In a heating system the combination of a boiler, a feed water line for the boiler, a 130

- closed container connected to the upper region of the boiler and to the feed water line, a valve operated by the container for controlling the feed water line consequent to water level variations in the boiler and for connecting the boiler to said container, and a vent connection rigidly swingable with the container and including a revoluble tubular section having its axis aligned with the axis of the valve.
13. In combination a boiler, a feed water line, a boiler overflow drain line, a single valve controlling the feed water line and drain line, a container connected to the boiler and valve for operating the valve, and a duplex counterpoise mechanism active on the container in stages to maintain it in a normal position.
14. In combination a boiler, a feed water line therefor, an overflow drain line for the boiler, a valve controlling the feed water line and the drain line, a container connected to the boiler under all operating conditions and means connecting the container to said valve whereby the water level in the container may correspond to the water level in the boiler under all operating conditions, a counterpoise for the container for maintaining the valve in closed relation to the feed water line when the water level in the boiler is substantially normal and a second counterpoise mechanism opposing a downward movement of the container but yieldable when a flooded condition exists in the boiler whereby the container may move downwardly and position said valve to connect the boiler with the overflow drain line.
15. In a device of the character described
- the combination with a boiler, of a feed water line therefor, an overflow drain line therefor, a common valve controlling the drain line and the feed water line, a hollow stem for the valve, a container mounted on the stem and communicating with the water line and boiler through said valve and a pipe line connected to the upper region of the container and associated with said valve stem, a pivotal connecting means associated with the stem and a pipe line connecting said pivotal means to the boiler whereby the pressure in the top region of the container may correspond to the pressure in the top region of the boiler.
16. In combination a boiler, a feed water line therefor, an overflow drain line for the boiler, a valve controlling the feed water line and the drain line, a container connected to the boiler under all operating conditions and means connecting the container to said valve whereby the water level in the container may correspond to the level in the boiler under all operating conditions including a hollow valve sleeve and valve stem, a counterpoise for the container for maintaining the valve in closed relation to the feed water line when the water level in the boiler is substantially normal, the counterpoise being secured to the valve stem and a second counterpoise mechanism mounted independently of the valve stem and opposing a downward movement of the container and yieldable when an overflow condition exists in the boiler.

JAMES P. QUALEY.
